UNITED STATES PATENT OFFICE.

JOSEPH J. RAUWALD AND JOHN RAUWALD, OF MILWAUKEE, WISCONSIN.

WALL SAFE.

1,404,480.

Specification of Letters Patent. Patented Jan. 24, 1922.

Application filed December 23, 1918. Serial No. 267,981.

To all whom it may concern:

Be it known that we, JOSEPH J. RAUWALD and JOHN RAUWALD, citizens of the United States, and residents of Milwaukee, in the county of Milwaukee and State of Wisconsin, have invented new and useful Improvements in Wall Safes, of which the following is a description, reference being had to the accompanying drawings, which are a part 10 of this specification.

The invention relates to safes more particularly for use in residences, and is fully described in the following specification and shown in the accompanying drawings in 15 which:

Fig. 1 is a front elevational view of a safe embodying the invention, parts being broken away; Fig. 2 is a section taken on the line 2—2 of Fig. 1; Fig. 3 is a section 20 taken on the line 3—3 of Fig. 2; Fig. 4 is a detail sectional view taken on the line 4—4 of Fig. 1; Fig. 5 is a section similar to Fig. 3 showing a modified form of construction, parts being broken away; Fig. 6 is a front 25 elevational view of a fragmentary portion of the construction shown in Fig. 5.

In the drawings the numeral 7 designates the wall joists of the building and the numeral 8 a third wall joist. The safe embodying the invention in each instance consists of a double wall box which is secured to the joists by fastening means rendered 30 accessible only on the opening of the door or doors of the safe.

The double walled box comprises an outer hollow frame 9, an outer casing 10, an inner frame 11 and an inner casing 12.

The outer casing 10 comprises a rear wall and top, bottom and side walls having their 40 front edges secured in grooves 13 in the frame 9 in any suitable manner as by welding. The frame 9 has a hollow interior 14 which may be filled with any suitable fire-proofing liquid or substance.

The inner casing 12 comprises a rear wall and top, bottom and side walls having their front edges secured to the frame 11 in any suitable manner as by screws 12'. The frame 11 is secured in spaced relation to the 45 casing 10 by means of bolts 15 passing through the back of the casing 10 and secured to flanges 16 on said frame 11 and also by screws 17 or other suitable fastening means to inwardly extending flanges 18 on 50 the frame 9. The outer frame 9 may be held

spaced away from the face of the wall of the building into which the safe is built by means of a marginal edge frame 19 interposed between the face of the wall of the building and the shoulders 20 on the 60 frame 9.

The outer casing 10 is provided with holes 21 for the insertion of screws 22 into the joists 7 to secure the safe in place and access to the screws is had through openings 23 in 65 the sides of the casing 12 which are normally covered after the screws are in place by means of plates 24 secured to the sides of the casing by screws 25. In addition a hole 26 may be provided in the back of the 70 safe to receive a screw 22', fastenable to the joist 8, access to this screw being had through an opening 23' in the back of the casing 12 normally covered by a plate 24' secured to 75 said casing by screws 25'.

In the construction shown in Figs. 1 to 4 inclusive access to the interior of the safe is had through the doors 27 and 28. Each of these doors is pivotally mounted upon the flanges 18 of the frame 9 by pins 28' passing through said flanges and connected to said doors. The doors have hollow interiors 29 adapted to be filled with any suitable fire-proofing liquid or substance and the door 28 has a flange 30 overlapping the other door 80 so that the locking of this flanged door secures both doors in place. The means for locking the door 28 consists of locking bolts 31 slidably mounted within the door and engageable in openings 32 in the frame 9 and 85 having rack extensions 33 at their inner ends engaging opposite sides of a gear 34 and means for controlling the operation of said gear. This means consists of the conventional form of cylindrical lock 35 mounted 90 within an inwardly projected sleeve 36 carried by the door and having the gear 34 secured to its spindle so that on the turning of the lock spindle by the key, the gear 34 will be rotated to either move the bolts 31 95 toward each other to remove said bolts from engagement with the frame 9 or to move said bolts 31 outwardly to locking position.

Means are provided for opening both doors on the opening of one of them consisting of a gear 37 mounted on one of the hinge pins 28' of each door and each engaging a rack 38 on a bar 39, as shown in Fig. 4.

In the construction shown in Figs. 5 and 110

6 the construction of the safe is similar to that previously described except that a single door 40 is used and in this instance the flange edge 41 of this door abuts against a 5 jamb 42 of the frame 9. The locking means for the single door is identical with that previously described for the double doors.

In the construction above described it will be noted that the means for securing the 10 safe to the wall of the building are only accessible upon the opening of the doors and the double wall construction provides heat insulating space surrounding the interior of the safe.

15 What we claim as our invention is:

1. A safe comprising a hollow outer frame adapted to receive fireproofing material within the interior thereof, an outer casing secured to said frame, an inner container, 20 means securing said container with its walls spaced from those of said outer casing and frame, and a door for said inner container.

2. A safe comprising an outer casing, an outer frame secured to the edges of said casing, an inner frame secured to said outer frame, an inner container within the outer casing with its walls spaced from the walls 25 of said casing and its edges secured to said

inner frame, and a door for said inner container.

30

3. A safe comprising an outer casing partially extending into a wall and being secured thereto, an outer frame secured to the outer edges of said casing, a marginal frame enclosing that part of said casing between 35 said outer frame and the wall, an inner frame secured to said outer frame, an inner container within the outer casing with its walls spaced from the walls of said casing and its edges secured to said inner frame, 40 and a door for said inner container.

4. A safe comprising an outer frame, an outer casing secured to said outer frame, an inner frame, an inner casing secured to said inner frame and having its walls spaced 45 from the walls of the outer casing, fastening means for securing the safe in a wall; said inner casing having openings through which said fastening means are applied, removable plates closing said openings, and a 50 door for the safe.

In testimony whereof, we affix our signatures.

JOSEPH J. RAUWALD.
JOHN RAUWALD.
